Assistant Examiner — Emily Anna Saunders

CLAIM

The ornamental design for a spinner and game card set as shown and described.

DESCRIPTION

FIG. 1 is a front view of a spinner and game card set showing my new design;

FIG. 2 is a right side view of the spinner and game card set;

FIG. 3 is a left side view of the spinner and game card set;

FIG. 4 is a top view of the spinner and game card set; and,

FIG. 6 is a top front side perspective view of the spinner and game card set.

The rear view of the spinner and game card set forms no part of the claimed design.
